UNITED STATES PATENT OFFICE.

CLARENCE E. HARSH, OF MINERVA, OHIO, ASSIGNEE OF ONE-HALF TO RALPH M. SCHORY, OF MINERVA, OHIO.

WINDOW-SHADE BRACKET.

Application filed July 24, 1920. Serial No. 398,731.

To all whom it may concern:

Be it known that I, CLARENCE E. HARSH, a citizen of the United States, residing at Minerva, in the county of Carroll and State 5 of Ohio, have invented a new and useful Window-Shade Bracket, of which the following is a specification.

This invention relates to window shade brackets and has for its objects the production 10 of a neat and simple form of shade bracket which can be secured to a window casing at any convenient point and which is provided with an adjustable bracket arm which may be easily and readily adjusted to 15 accommodate shade rollers of varying lengths, a simple and effective clamping device being provided upon said bracket arm for clamping it in any desired position.

With these objects in view the invention 20 consists in the novel construction and arrangement of parts, hereinafter described, illustrated in the accompanying drawings, and particularly pointed out in the appended claims, it being understood that various changes in the form, proportions, size 25 and minor details of construction may be made within the scope of the appended claims, without departing from the spirit or sacrificing any of the advantages of the invention.

The invention thus set forth in general terms is illustrated in the accompanying drawings forming part hereof, in which—

Figure 1 is a perspective view of a bracket 30 embodying the invention, showing the same mounted in position upon a portion of a window casing.

Fig. 2 is a detached perspective view of the bracket arm and clamping device.

Fig. 3 is a vertical transverse section 40 through the bracket in the opened or unclamped position; and

Fig. 4, a similar view showing the bracket arm clamped upon the base plate.

A practical embodiment of the invention 45 is disclosed in the accompanying drawings, forming a part of this specification in which similar numerals of reference indicate corresponding parts throughout the several views.

A portion of an ordinary window sash is indicated at 1 and an elongated substantially rectangular, horizontally disposed base plate is shown at 2, said base plate having 50 the straight body portion 3 and the off-set

ears 4 provided with suitable apertures through which screws 5 or the like are attached to secure the same to the window casing. With this construction it will be seen that the body portion 3 of the base plate is 60 spaced from and parallel with the surface of the window casing.

Removably mounted upon the base plate is a bracket member comprising the U-shaped spring member 6 and the bracket arm 7 having an in-turned angular flange 8 which is connected to the outer leg 9 of the U-shaped member by means of rivets 10 or the like.

The outer extremity of the bracket arm 7 is provided with an aperture 11 or with the usual slot to accommodate the gudgeons at the respective extremities of the roller of the shade. The bracket arms 7 are of such a length that when the shade is supported thereby the latter will depend and hang free 75 of the inner sash.

The inner leg 12 of the U-shaped spring member 6 is provided at its upper extremity with the tubular portion 13 within which is pivotally mounted the link 14, the outer 80 free end of said link being located through the ears 15 of the lever 16, said lever having an angularly disposed finger portion 17 by means of which it may be easily operated. The inner extremity of the lever 16 is arranged to engage the outwardly curved lip 18 formed upon the upper extremity of the leg 9 of the U-shaped spring member.

The U-shaped spring member 6 is mounted upon the body portion 3 of the base plate as 90 shown in the drawings, the lever 16 being placed in the raised position as best shown in Fig. 3, allowing the U-shaped member and bracket arm to be slid along the base plate to the desired point when the lever 16 is 95 depressed to the position shown in Fig. 4, the inner end thereof engaging the curved lip 18 and clamping both legs of the U-shaped member tightly upon the body portion 3 of the base plate holding the bracket arm in 100 the desired position. In order to change the adjustment of the bracket arm the lever 16 is raised in the position shown in Fig. 3 when the bracket arm and U-shaped member may be slid upon the body portion of 105 the base plate after which the lever is again moved to the lowered position clamping the U-shaped member tightly upon the base plate.

It will be evident from the foregoing that 110

the bracket arm may be attached or detached with ease and expedition and may be quickly and readily moved to any desired adjusted position and again tightly 5 clamped in place upon the base plate.

Although the drawings and above specification disclose the best mode in which I have contemplated embodying my invention I desire to be not limited to the details of 10 such disclosure, for, in the further practical application of my invention, many changes in form and construction may be made, as circumstances require or experience suggests, without departing from the spirit of 15 the invention, within the scope of the appended claims.

I claim:—

1. A shade bracket comprising a base plate, a vertically disposed U-shaped member 20 located around said base plate and arranged for horizontal, slidable movement thereon, a bracket arm rigidly mounted upon the outer leg of said U-shaped member, a link pivotally connected to the extremity of the

inner leg of the U-shaped member, and a 25 lever carried upon said link and arranged to engage the end portion of the outer leg of the U-shaped member to clamp the legs of said U-shaped member tightly upon the base plate.

2. A shade bracket comprising a base plate, a vertically disposed U-shaped spring member located around said base plate and arranged for horizontal, slidable movement thereon, a bracket arm rigidly mounted upon 30 the outer leg of said U-shaped member, the outer end of said outer leg being outwardly curved, a tubular portion formed at the upper end of the inner leg of said U-shaped member, a link pivotally connected 35 to the extremity of the inner leg within said tubular portion, and a lever carried upon said link and arranged to engage the outwardly curved end of the outer leg to clamp the legs tightly upon the base plate. 40

In testimony that I claim the above I have hereunto subscribed my name.

CLARENCE E. HARSH.
